DESK LAMP

Shoji Ishikawa, Nara, Japan, assignor to Matsushita
Electric Industrial Co., Ltd., Osaka, Japan

Filed July 12, 1972, Ser. No. 271,327

Term of patent 14 years

Int. Cl. D26—05

U.S. Cl. D48—20 F

Fig. 1

Fig. 2

Fig. 3

Fig. 4

FIG. 1 is front elevational view of a desk lamp showing my new design;

FIG. 2 is a rear elevational view thereof;

FIG. 3 is a side elevational view thereof, the opposite side being identical thereto; and

FIG. 4 is a top, oblique perspective view thereof.

I claim:

The ornamental design for a desk lamp, as shown.
